UNITED STATES PATENT OFFICE.

FAY C. HAYES, OF ALTAMONT, NEW YORK.

COLLAPSIBLE BUCKET.

1,167,497.

Specification of Letters Patent. Patented Jan. 11, 1916.

Application filed December 11, 1913. Serial No. 806,942.

To all whom it may concern:

Be it known that I, FAY C. HAYES, a citizen of the United States, residing at Altamont, in the county of Albany and State of New York, have invented certain new and useful Improvements in Collapsible Buckets, of which the following is a specification.

It is the object of this invention to provide a bucket which may be grasped and held by one hand while water is being transferred therein from a source of supply to a point of deposition.

It is one of the special objects of my invention to provide a hand-grasp bucket which is especially adapted to be held by one hand under the mouth of a pump or dipped into a supply of water for filling a radiator tank of an automobile, or for other purposes for which such a device may be advantageously utilized.

A further object of my invention is to provide a bucket of this kind with a pouring spout to facilitate emptying or pouring the contents of the bucket into an intake of relatively small size.

A still further object is to provide a bucket of this character with stiffening means which is proportioned to at least equal one dimension of the body of the bucket so that the latter may be folded about the stiffening means as a frame, into a flat condition so as to be carried in the pocket of the user or in a pocket in the automobile or car.

The object of this invention is to provide a bucket which is adapted to be manipulated and held and carried by one hand grasped about the stiffening means thereof, in contradistinction to those forms of bucket in which the open top is of such area that bails or special handles are necessary.

Other features and objects of this invention will be more fully described in connection with the accompanying drawing and will be more particularly pointed out and ascertained in and by the appended claims.

In the drawing: Figure 1 is a perspective view of a hand-grasp bucket embodying one form of my invention. Fig. 2 illustrates the bucket in a folded condition. Fig. 3 is a sectional view on line 3-3 of Fig. 1. Fig. 4 is a plan view.

Like characters of reference designate similar parts throughout the different figures of the drawing.

As illustrated, 1 designates the body of a bucket embodying my invention which is

formed of foldable material of a water-proof nature, such for instance as canvas, or any material which is foldable or collapsible. The containing body 1 may be formed of two halves or parts which may be connected by a seam 2, as illustrated more particularly in Fig. 3. The top of said bucket is open and is provided with stiffening means which not only serves to maintain the top open and spread apart but which also functions as a frame about which the body portion may be folded into a flat condition.

As illustrated, the stiffening means is in the form of a rod 3 which is embraced by the upper margin 4 so as to inclose the stiffening rod 3 and protect the same from rust. In order to secure the stiffening rod 3 to the body portion 1, I may extend the marginal edges 5 downwardly on the outside of the body portion 1 and fasten the marginal edges 5 to the body by means such as rivets or clips 6. Loops 7 may be attached, by means of the fastening device 6, so as to hang the bucket up to dry or for any other reason when it is not desired to carry the bucket in the pocket of the user.

One of the novel features of this invention resides in the construction of the stiffening means whereby the same at one end portion 8 of the bucket will lie between the fingers and palm of the hand of the user so as to be grasped thereby, whereas the other portion will serve as a pouring spout to facilitate pouring the contents into an intake of relatively small size.

As illustrated, that portion indicated at 8 is proportioned so that it may be grasped between the palm and the fingers of the hand whereas that portion indicated at 9, 95 converges to form a pouring portion or spout. Thus in use, the bucket can be held in the right hand while it is being filled and can be tilted from the position shown in Fig. 1, to an inclined position, when it is desired to pour the contents of the bucket into a receiver.

The length of the spread or stiffened open portion, from the left to the right of Fig. 1, equals one dimension of the body portion 1 so that it may act as a frame or a form about which the body portion may be folded into a relatively flat condition. Thus a more compact structure results than would be the case if the bucket or body portion were promiscuously collapsed and the folded article can be readily inserted into a

5 pocket of relatively small containing capacity. Furthermore, in folding the bucket as indicated, the wet interior, including the open top, will lie beneath a number of folds of dry exterior portions of the body portion so that small quantities of water will be prevented from spilling into the pocket into which the bucket has been inserted.

10 It will thus be seen that the device of my invention is wholly different from those containers and buckets which have open tops or such areas that a bail is required in order to carry the same, or of such areas where when a bail is omitted it is necessary 15 to carry the same with two hands. In other words, one of the distinctive features of my invention resides in a construction whereby a single hand-grasp is sufficient to not only carry but manipulate the bucket.

20 While I have herein shown and described one specific form of my invention, I do not wish to be limited thereto except for such limitations as the claims may import.

I claim:—

25 1. In a collapsible bucket, the combination of a containing body of foldable material having an open top, means for stiffening and holding the top open and proportioned to be grasped between the palm and 30 fingers of the hand of the user, the stiffen-

ing means being equal to the body in one dimension to act as a frame or form about which the body may be folded, said body being substantially of a greater length in one direction than the other, substantially as 35 described.

2. In a collapsible bucket, the combination of a containing body of flexible material having an open top, stiffening means associated with the upper marginal edge of 40 said body of such shape as to snugly fit between the fingers and palm of the hand of a user, said stiffening means converging at one end and shaped to conform to said body and provide a mouth therefor.

3. In a collapsible bucket, a containing body of flexible material having an open end, a stiffening rod on the upper marginal edge thereof, said rod being of elongated substantially elliptical contour and having a 45 tapering portion formed to provide a mouth, said rod being of such shape as to be readily grasped between the fingers and palm of the user's hand.

In testimony whereof I affix my signature in presence of two witnesses.

FAY C. HAYES.
